UNITED STATES PATENT OFFICE.

JULIA BAUM, OF BROOKLYN, NEW YORK.

DOLL'S DRESS.

1,300,915.

Specification of Letters Patent. Patented Apr. 15, 1919.

Application filed November 26, 1918. Serial No. 264,157.

To all whom it may concern:

Be it known that I, JULIA BAUM, a citizen of the United States, and a resident of the city of New York, borough of Brooklyn, in 5 the county of Kings and State of New York, have invented a new and Improved Doll's Dress, of which the following is a full, clear, and exact description.

The object of the invention is to provide 10 a new and improved doll's dress arranged to strikingly enhance the appearance of the doll. Another object is to provide a dress which forms a permanent part of the doll.

With these and other objects in view, the 15 invention consists of certain novel features of construction as hereinafter shown and described and then specifically pointed out in the claims.

A practical embodiment of the invention 20 is represented in the accompanying drawings forming a part of this specification, in which similar characters of reference indicate corresponding parts in all the views.

Figure 1 is a front elevation of the doll's 25 dress;

Fig. 2 is an enlarged cross section of the same on the line 2—2 of Fig. 1;

Fig. 3 is an enlarged sectional plan view of the same on the line 3—3 of Fig. 1;

30 Fig. 4 is a side elevation of a modified form of dress with parts open and parts shown in section; and

Fig. 5 is an enlarged front view of a portion 35 of the braid of which the dress is made.

The doll's dress illustrated in Figs. 1, 2 and 3 forms a permanent part of the doll and it comprises a body 10, sleeves 11 and legs 12 made of braid, the strands of which are of silk, satin or other suitable woven

40 textile material. The braid for forming the dress portions 10, 11 and 12 is wound around the corresponding parts of the doll thus providing layers having their adjacent edges abutting and preferably fastened together

45 by stitches to securely hold the dress parts in position on the doll. In order to enhance the appearance of the dress, use is made of a short skirt 13 of woven textile material, preferably of the same nature as that of 50 which the strands of the braid are made. The skirt 13 has its upper end sewed or otherwise fastened to the under side of the lowermost layer of the body 10 so that the skirt surrounds the upper portions of the 55 legs 12, as plainly indicated in Figs. 1 and 2.

The lower portions of the legs 12 of the dress overlie the upper ends of stockings 14 held on the feet of the doll and preferably made of a woven textile fabric similar to that of which the strands of the braid are 60 made. Shoes 15 are also provided to complete the apparel of the doll. The hat 16 for the doll is likewise made of braid arranged in layers with the edges abutting and fastened together by stitches. 65

In the modified form shown in Fig. 4, the braid is arranged in layers on a foundation or lining 20 and in this case the braid is open along the median front or back line to permit of opening or closing the dress. 70 Suitable closing devices such as hooks and eyes, snap buttons or the like are provided at the adjacent edges of the opening and closing flaps to hold the latter in closed relation. It is understood that various forms 75 can be given to the dress thus made and hence I do not limit myself to any particular style of dress.

In practice, the braid is preferably made of two, three or more strands preferably of 80 different colors to strikingly enhance the appearance of the dress.

Having thus described my invention, I claim as new and desire to secure by Letters Patent:— 85

1. A dress for dolls, comprising a body having sleeves and legs and formed of braid of a textile material, the braid being arranged in layers around the body, arms and legs, the adjacent edges of the braid being 90 arranged in abutting relation, and fastening means fastening the braid in position to hold the body, arms and legs of the dress together.

2. A dress for dolls, comprising a body 95 having sleeves and legs and formed of braid of a textile material, the braid being arranged in layers around the body, arms and legs of the doll, the adjacent edges of the braid being arranged in abutting relation, 100 and stitches fastening the abutting edges together.

3. A dress for dolls, comprising a body having sleeves and legs and formed of a braid of textile material, the braid being arranged in layers around the body, arms and legs of the doll, the adjacent edges of the braid being arranged in abutting relation, 105 stitches fastening the abutting edges together, and a skirt of a woven textile mate- 110

rial attached to the lowermost layer of the said dress body and surrounding the upper portions of the said legs of the dress.

4. A dress for dolls, comprising a body having sleeves and legs and formed of braid of a textile material, the braid being arranged in layers around the body, arms and legs of the doll, the adjacent edges of the braid being arranged in abutting relation, 10 stitches fastening the abutting edges together, a skirt of a woven textile material attached to the lowermost layers of the said dress body and surrounding the upper portions of the said legs of the dress, and stockings overlaid by the lowermost portions of the said legs of the dress.

5. A dress for dolls, comprising a body having sleeves and legs and formed of braid of a textile material, the braid being arranged in layers around the body, arms and legs of the doll, the adjacent edges of the braid being arranged in abutting relation, 20 stitches fastening the abutting edges together, a skirt of a woven textile material attached to the lowermost layer of the said dress body and surrounding the upper portions of the said legs of the dress, and stockings overlaid by the lowermost portions of the said legs of the dress, the stockings being made of the material of which the braid is 25 made.

JULIA BAUM.
